UNITED STATES PATENT OFFICE.

HARRY W. BREWER, OF HUTCHINSON, KANSAS.

PENCIL-PRINTING MACHINE.

1,068,851.

Specification of Letters Patent. Patented July 29, 1913.

Application filed January 26, 1912. Serial No. 673,591.

To all whom it may concern:

Be it known that I, HARRY W. BREWER, a citizen of the United States, residing at Hutchinson, in the county of Reno and State of Kansas, have invented certain new and useful Improvements in Pencil-Printing Machines, of which the following is a specification.

My invention relates to pencil printing machines, and embodies means for printing one or more colors upon a pencil, or the like.

In order that the invention may be fully understood, reference will now be made to the accompanying drawings, in which:

15 Figure 1 is a plan view of my machine. Fig. 2 is a side elevation of the machine. Fig. 3 is a cross section on line III—III of Fig. 1. Fig. 4 is an irregular longitudinal section on line IV—IV of Fig. 1, and Fig. 20 5 is a detail of a lever and pawl to actuate one of the inking-disks of the machine.

In carrying out my invention I employ a frame 1, each side of which is provided at its inner side with a pair of longitudinal 25 rails 2, traversed by a reciprocating carriage 3, actuated by a crank-shaft 4 through the intermediacy of a connecting-rod 5, pivotally-secured at its forward end to a pair of arms 6, secured at their forward ends to 30 opposite sides of carriage 3.

7 designates a support carrying at its underside plural sets of type, symbols, or other printing means, for printing the pencils in one or more colors. In the drawing I have 35 shown two sets of type 8 and 9. Support 7 is pivotally-mounted at its ends upon a rod 10, so that it may be swung upward to gain access to the type at the underside thereof, but is normally held downward in printing 40 position by a pair of links 11, pivotally-secured by bolts 12 to the outer sides of frame 1. Rod 10 is carried by a pair of brackets 10^a secured to the opposite sides of frame 1. Links 11 have lugs 13 upon which 45 the adjacent side of the support 7 is reliably-held in printing position by set-screws 14, extending down through the upper portions of the links.

15 and 16 designate rotatable inking-disks 50 supported by two transverse bars 17 and 18, respectively, which assist in uniting the sides of frame 1. The inking-disks 15 and 16 are provided at their undersides with circular rows of ratchet-teeth 19 and 20, respectively, 55 teeth 19 being reversely-disposed to the teeth 20, so that the inking-disks will be alter-

nately rotated step by step as will herein-after appear.

21 and 22 designate a pair of gravity-pawls engaging teeth 19 and 20, and mounted upon a pair of oscillatory levers 23 and 24, secured to the transverse bars 17 and 18 by bolts 25 and 26, respectively. Levers 23 and 24 extend through slots 27 and 28, respectively, in one side of frame 1, and are 60 actuated by a reciprocating rod 22^a, slidably-mounted in a pair of guides 29, and having a link connection 30 at one end to the lower terminal of a lever 31, fulcrumed at 32 and having a bifurcated upper terminal 33 engaging the opposite sides of an eccentric 34, fixed upon one end of crank-shaft 4, which latter is provided at its opposite end with a drive pulley 35.

36 designates two ink-distributing rollers 75 journaled in the forward end of carriage 3 to take ink from the inking-disk 15 and distribute the same upon the type 8; and 37 designates two ink-distributing rollers for taking ink from the inking-disk 16 and distributing the same upon the type 9.

38 designates two pairs of disks for carrying the pencils into and out of engagement with the type 8 and 9, a pencil A being shown in position upon said disks, in Fig. 4. 85 Disks 38 are mounted upon two shafts 39, journaled in the opposite sides of the carriage 3, which opposite sides are united by a pair of braces 40. Disks 38 are adjustably-secured to shafts 39, so that the disks on 90 each shaft may be moved toward or away from each other to accommodate pencils of different lengths, care being taken, however, not to set the disks close enough together to come into contact with and blur the printed 95 portions of the pencils.

41 designates a pair of rockingly-mounted unloading arms for lifting the printed pencils from the disks 38 and depositing them upon a runway 42, which conducts the pencils to any desired point. Arms 41 are adjustably secured to a shaft 43, so that they may be adjusted toward or away from each other with the disks 38, to accommodate pencils of different lengths. Shaft 43 is mounted in a pair of bearings 44 and provided near one end with a crank-arm 45, rocked up and down intermittently by a vertically-arranged stem 46, actuated by a spring 47 and a cam 48, which latter is fixed upon one end 100 of a stub-shaft 49, journaled in one side of frame 1 and provided at its opposite end 110

with a bevel gear 50, intermeshing with a bevel gear 51 fixed upon one end of a shaft 52, journaled in a bearing 53 and provided at its opposite end with a bevel gear 54, 5 driven by a bevel gear 55, fixed upon the crank-shaft 4. Stem 46 extends through a guide 56 and is provided at its underside with an antifriction roller 57, engaging the periphery of cam 48. Spring 47 is interposed between guide 56 and the yoke 58 carrying the roller 57.

The operation briefly stated, is as follows: When the carriage is drawn backward to the reverse position shown in Fig. 4, a pencil 15 cil is deposited upon the disks 38, so that when the same moves forward with the carriage to the position shown in Fig. 4, said pencil will be carried into and out of contact with the two sets of type 8 and 9, which 20 print the pencil in different colors. As the pencil contacts with type 9, it is rotated thereby and presents a different surface to the type 8, so that the same will not obliterate the printing performed by the type 9. 25 As the carriage 3 approaches the rear end of its movement, the pencil is brought into position over the curved terminals of the unloading arms 41, the actuating mechanism of which is so timed as to cause said arms to 30 lift the pencil from the disks 38 before the carriage moves backward. When the free ends of the unloading arms 41 move upward a certain height, the pencil rolls downward off the same onto the runway 42, which, as 35 hereinbefore stated carries it to any desired point. As the inking-disks 15 and 16 have been supplied with different colored inks, a portion of the ink from disk 15 is taken up for type 9 by the distributing-rollers 37 at 40 each forward movement of the carriage 3, and a portion of the ink is taken up from disk 15 for type 8, by the distributing rollers 36 at each rearward movement of the carriage, the movement of the carriage being 45 of such length that the upper roller 37 is not brought into contact with the type 8, and the upper roller 36 is not brought into contact with the type 9.

The actuating mechanism which intermittently rotates the disks 15 and 16 is so

timed with relation to the movement of the carriage 3, that it will actuate disk 15 when the lowermost ink-distributing roller 36 is out of engagement therewith, and actuate disk 16 when the lowermost ink-distributing 55 roller 37 is out of engagement therewith, and although the pawls 21 and 22 are simultaneously actuated by their respective levers 23 and 24, when one of said pawls positively engages the ratchet teeth of its respective 60 inking-disk, the other pawl idly slides over the ratchet teeth of its respective inking-disk and vice versa.

Having thus described my invention what I claim and desire to secure by Letters Patent, is:

1. In a machine of the character described, stationary printing means for printing one or more colors on a pencil, or the like, rotatably-mounted disks to carry said pencil 70 into and out of engagement with said printing means, and unloading arms to lift the pencil from said disks.

2. In a machine of the character described, stationary printing means for printing one 75 or more colors on a pencil, or the like, movable means to carry said pencil into and out of engagement with said printing means, rockingly-mounted unloading arms to remove the printed pencil from said movable 80 means, and means timed with said movable means to actuate the unloading arms.

3. In a machine of the character described, printing means for printing one or more colors on a pencil, or the like, movable means 85 to carry a pencil into and out of engagement with said printing means, rockingly-mounted arms to remove the printed pencil from said movable means, a stem for actuating said arms, a guide through which said stem 90 extends, resilient means for moving said stem in one direction, and a cam to move the stem in the opposite direction.

In testimony whereof I affix my signature, in presence of two witnesses.

HARRY W. BREWER.
